UNITED STATES PATENT OFFICE.

ARTHUR BALTHAZAR, OF CHICOPEE FALLS, AND MYRON R. SHAW, OF SPRINGFIELD, MASSACHUSETTS, ASSIGNORS TO THE FISK RUBBER COMPANY, OF CHICOPEE FALLS, MASSACHUSETTS, A CORPORATION OF MASSACHUSETTS.

DESIGN FOR A TIRE.

57,571.

Specification for Design.

Patented Apr. 26, 1921.

Application filed September 28, 1920. Serial No. 413,412. Term of patent 14 years.

To all whom it may concern:

Be it known that that we, ARTHUR BALTHAZAR, a citizen of the United States, residing at Chicopee Falls, county of Hampden, and State of Massachusetts, and MYRON R. SHAW, a citizen of the United States, residing at Springfield, county of Hampden, and State of Massachusetts, have invented a new, original, and ornamental Design for a Tire, of which the following is a specification, reference being had to the accompanying drawing, forming part thereof.

Figure 1 is a plan view showing a portion of a tire casing embodying our design; and

Fig. 2 is a section on line 2—2 of Fig. 1.

We claim—

The ornamental design for a tire as shown.

ARTHUR BALTHAZAR.
MYRON R. SHAW.
